JOHN F. O'CONNOR, OF CHICAGO, ILLINOIS, ASSIGNOR TO WILLIAM H. MINER, OF CHAZY,
NEW YORK.

ROCKER SIDE BEARING.

1,308,640.

Specification of Letters Patent.

Patented July 1, 1919.

Application filed September 21, 1918. Serial No. 255,042.

To all whom it may concern:

Be it known that I, JOHN F. O'CONNOR, a citizen of the United States, residing at Chicago, in the county of Cook and State of Illinois, have invented a certain new and useful Improvement in Rocker Side Bearings, of which the following is a full, clear, concise, and exact description, reference being had to the accompanying drawings, 10 forming a part of this specification.

This invention relates to improvements in rocker side bearings.

One object of this invention is to provide an efficient rocker side bearing for railway 15 cars and which comprises a minimum number of parts.

Another and more specific object of the invention is to provide a rocker side bearing for railway cars which will have an action 20 similar to that of a side bearing employing a true anti-friction roller and which at the same time possesses the usual characteristics of a rocker bearing by which the anti-friction element is adapted to automatically 25 turn itself to normal position under the influence of gravity.

In the drawing forming a part of this specification, Figure 1 is a vertical, sectional view, taken through the end portions of a 30 car body and truck bolster, showing my improvements in connection therewith. And Fig. 2 is a vertical, sectional view, taken substantially on the line 2—2 of Fig. 1.

In said drawing, 10 denotes the upper portion 35 of a truck bolster of a railway car and 11 the under portion of an opposed body bolster. The improved side bearing is attached to the body bolster and, as illustrated in the drawing, consists of two elements, a 40 retaining and supporting member A and the rocker B. A cotter C is employed but the same does not form any part of the side bearing proper in the true sense.

The retaining member A is preferably in 45 the form of a casting and is provided with perforated ears or lugs 12—12 by which it is adapted to be riveted to the body bolster. Said member A is formed with a depending hollow housing or casing, as clearly shown 50 in Fig. 1, the same comprising a vertical side or end wall 13 and a circular bottom wall 14, the latter being cut away at its lower portion, as indicated at 15, and adapted to form limiting shoulders 16—16. Said housing or 55 casing is open at one side or end as shown in

Figs. 1 and 2. On its interior, the housing of said member A is formed with a lower circular surface 17 and also with a curved bearing surface 18 in the upper wall thereof.

The rocker B is formed with an enlarged 60 lower end, as clearly shown in Fig. 1, the under face of which is curved to form a bearing surface, as indicated at 19, and adapted to contact with the truck bolster. The member B is formed at its upper end 65 with an enlargement 20, said enlargement 20 having an upper curved bearing surface 21 and a lower curved surface 22. The bearing surfaces 19 and 21 of the rocker B are not only concentric but are formed of the same 70 radius so that they, in reality, constitute separated portions of the surface of a true cylinder. With this construction, it is evident that the action of the rocker B is similar to that of a true anti-friction, cylindrical 75 roller.

The enlarged upper and lower ends of the rocker B are connected by a tapered section, as indicated at 23, which swings within the opening 15 of said retaining member A, the 80 sides of said connecting section 23 being adapted to engage the shoulders 16 upon extreme movement of the rocker. The curved surface 22 of the rocker corresponds to the curved surface 17 of the retaining member 85 and is adapted to facilitate the swinging movement of the rocker as it returns to normal.

The curved surface 21 of the rocker B subtends a relatively small angle and on either 90 side thereof the rocker B is formed with shouldered portions 24—24 which are adapted to coöperate with the end portions of the bearing surface 18 of the retaining member A and assist in limiting the movements of 95 the rocker B, as will be understood. The parts are assembled by sliding the rocker endwise or sidewise within the housing of the retaining member A, after which the cotter C can be introduced through suitable 100 perforations in the curved wall 14 of said member A.

In normal condition of the parts, there is a slight clearance between the bearing surface 21 of the rocker and the bearing surface 18 of the member A. When the bearing comes into play, it is evident that the rocker will swing with respect to the member A while at the same time the action of an anti-friction cylindrical roller is produced. 110

By curving the bearing surface 18 in the manner shown, I reduce the length of the required surface 21 and also permit of a slight bodily elevation of the rocker B so as 5 to facilitate its return to normal under the influence of gravity. As soon as pressure is released, it is evident that the rocker B will seat itself upon the curved bearing surface 17 of the member A and will swing back to 10 normal in the manner of a pendulum.

The device is exceedingly simple, easy to manufacture and embodies the advantages of a true cylindrical roller and rocker side bearing without the disadvantages of the 15 usual roller bearing which requires springs or other devices for returning the anti-friction elements to normal after each actuation. The arrangement is also compact while at the same time I maintain a wide range of 20 action.

I claim:

1. In a device of the character described, adapted to be interposed between two relatively movable elements, the combination 25 with a retaining member adapted to be secured to one of said elements, of a rocker, said member and rocker having coöperating but oppositely curved bearing surfaces, said rocker having also another curved bearing 30 surface adapted to engage the other of said elements, the two curved bearing surfaces of the rocker being concentric.

2. In a device of the character described, the combination with a retaining member, of 35 a rocker associated therewith, said member and rocker having integral means for detachably connecting the same and adapting the rocker for swinging movement with re-

spect to said member, said means including a recess formed within said member and 40 open at one side and a corresponding head on the rocker insertible sidewise within said recess.

3. In a side bearing adapted for railway cars and the like, the combination with a retaining member adapted to be secured to the under side of a body bolster or the like, of a rocker associated with said member, said rocker having upper and lower curved concentric bearing surfaces, said retaining 45 member having an interior bearing surface coöperable with said upper bearing surface of the rocker, said member having also a curved surface below the bearing surface thereof and said rocker having a coöperating 50 curved surface disposed intermediate said upper and lower concentric bearing surfaces of the rocker.

4. In a device of the character described, the combination with a retaining member 60 having an upwardly curved bearing surface on its under side, of an anti-friction element associated with said member, said element having upper and lower concentric bearing 65 surfaces struck on equal radii, the upper of said surfaces coacting with the bearing surface of said member, integral means on said member and element adapting said element to be swingingly supported from said member and integral means on said member and element limiting the swinging movement of 70 said element with respect to said member.

In witness that I claim the foregoing I have hereunto subscribed my name this 3rd day of Sept. 1918.

JOHN F. O'CONNOR.
